(57) **CLAIM**

The ornamental design for a cosmetics brush, as shown and described.

DESCRIPTION

FIG. 1 is a perspective view of a cosmetics brush showing the new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational thereof;

FIG. 7 is a rear elevational view thereof;

FIG. 8 is a second perspective view of a cosmetics brush according to a second embodiment of the present design.

FIG. 9 is a left side elevational view thereof;

FIG. 10 is a right side elevational view thereof;

FIG. 11 is a top plan view thereof;

FIG. 12 is a bottom plan view thereof;

FIG. 13 is a front elevational view thereof; and,

FIG. 14 is a rear elevational view thereof.

The broken lines depicting a brush handle represent unclaimed portions of the design.

1 Claim, 5 Drawing Sheets
